F. H. WELCH.
HORSE COLLAR PROTECTOR.
APPLICATION FILED SEPT. 15, 1915.

1,216,898.

Patented Feb. 20, 1917.

UNITED STATES PATENT OFFICE.

FRANK H. WELCH, OF ALTUS, OKLAHOMA.

HORSE-COLLAR PROTECTOR.

1,216,898.

Specification of Letters Patent. Patented Feb. 20, 1917.

Application filed September 15, 1915. Serial No. 50,844.

To all whom it may concern:

Be it known that I, FRANK H. WELCH, a citizen of the United States, residing at Altus, in the county of Jackson and State of Oklahoma, have invented new and useful Improvements in Horse-Collar Protectors, of which the following is a specification.

The invention relates to a horse collar, 10 and more particularly to the class of horse collar protectors.

The primary object of the invention is the provision of a collar of this character wherein one of the seams without the same 15 is formed with a casement receiving therein a wire spring yoke which materially reinforces the collar, and on the throat point of the said collar is arranged a wearing flap for the pole strap so that the cutting 20 through the collar at this point by the frictional contact of the strap therewith is prevented.

Another object of the invention is the provision of a collar of this character wherein 25 in the construction thereof is novel in form to assure maximum wearing qualities, strength and durability.

A further object of the invention is the provision of a collar of this character which 30 is simple in construction, protected at the points of strain thereon, thoroughly reliable and efficient in its purpose, and inexpensive in manufacture.

With these and other objects in view, the 35 invention consists in the construction, combination and arrangement of parts as will be hereinafter fully described, illustrated in the accompanying drawing, and pointed out in the claim hereunto appended.

40 In the drawing:—

Figure 1 is a side elevation of a collar constructed in accordance with the invention.

Fig. 2 is a vertical transverse sectional view through the same.

Fig. 3 is a vertical longitudinal sectional view therethrough.

Fig. 4 is a perspective view of the wire spring.

50 Fig. 5 is a perspective view of the wearing flap and fastener therefor.

Fig. 6 is a fragmentary vertical sectional view showing a slight modification of the horse collar protector.

Similar reference characters indicate corresponding parts throughout the several views in the drawing. 55

Referring to the drawing in detail, the collar comprises a padded body A formed as usual with hip wings B, neck rim C 60 joined to the body A through the medium of inner and outer seams 5 and 6, respectively, the latter seam being formed with a casement 7 in which is received a wire spring yoke 8 which reinforces the body A of the 65 collar.

The body A of the collar is open diametrically opposite the throat side thereof and is adjustably connected together through the medium of the connections 9 of the ordinary well-known construction. 70

At the throat side of the body A of the collar interiorly thereof is a wearing flap or section 10, preferably made from leather, and has passed centrally therethrough a 75 screw or bolt 11, the head of which is engaged in a substantially diamond-shaped washer 12 formed with down-turned spurs 13 at its corners to bite into the flap or section 10, and this screw or bolt 11 is passed 80 through the body A of the collar at the throat and has engaged thereon a hook member 14 which is held upon the screw and has its hook overlying the seam 6, while the opposite end of the member 14 lies 85 against the rim C of the body A of the collar. It is of course understood that the hames are placed about the collar in the usual well-known manner when the body A of said collar is fastened about the neck of 90 the animal. The flap or section 10 prevents wear on the throat portion of the collar by the pole strap when engaged therewith, while the wire yoke 8 materially reinforces the collar. 95

In Fig. 6 there is shown a slight modification of the invention wherein the wearing flap or section 10' is mounted within the collar in identically the same manner as the wearing flap or section 10, with the wearing plate 12' superimposed upon the section 10', and through both of which passes a bolt 11' which has engaged therewith a spring wire clip 13' coiled about the wire yoke 8', as shown, and also has a portion 14' surrounding the bolt 11' which carries the usual adjustable nut 15 thereon. 100

From the foregoing description, taken in

connection with the accompanying drawing, the construction and manner of use of the device will be clearly understood, and therefore a more extended explanation has 5 been omitted.

What is claimed is:—

The combination with a horse collar having a yoke casement exteriorly thereof and a spring yoke therein, of an attachment 10 comprising a flexible wearing section disposed against the inner face of the closed end of the collar, a rigid wearing plate superimposed upon the section and having a central aperture, a bolt member passed 15 through the aperture, and also through the collar and having its head flush with the

exposed surface of the wearing plate, a clip adjustably engaged on the bolt member and acting against the body of the collar and the said yoke casement to hold the wearing 20 section and plate in position relative to each other and also to the collar, and spurs bent from the wearing plate and engageable in the flexible section to prevent the turning thereof.

25

In testimony whereof I affix my signature in presence of two witnesses.

FRANK H. WELCH.
